WELL PACKING DEVICE

Emmett J. Roe, Wichita, Kans., assignor of one-half to P. A. McKenna

Application March 4, 1937, Serial No. 129,033
Renewed February 21, 1940

12 Claims. (Cl. 166—13)

This invention relates to a mechanical packing device for plugging or sealing oil and gas well holes to exclude the entrance of water into the well.

5 In practice, it is found that during the drilling of oil or gas wells, or after the well has been drilled, it frequently happens that water will break through the oil bearing sands and enter the well, resulting in a mixing of the water with 10 the oil, as well as a reduction in the flow of oil which is highly objectionable and costly to the oil producers.

Heretofore, various methods have been employed to shut off the flow of water into the well, 15 but these have not proved very successful and are very difficult and costly to apply. The two most successful methods, of which I know at the present time, are the lead wool and cement methods. The lead wool is applied by lowering the wool in 20 a screen container to the bottom of the well and then driving the same into sealing engagement with the walls of the well by use of a heavy string of cable drilling tools. As the sand wall of the well is soft, the driving operation has a 25 tendency to weaken the wall and sooner or later results in the water breaking through around the plug. When plugging a well with cement there is great danger of some of the cement getting into the walls of the oil bearing sands and reducing the flow of oil.

It is the primary object of the present invention to provide a mechanical plug which may be easily installed in the well to be plugged and when installed will effectively seal the well and 30 shut off the flow of water.

A further object of the invention resides in providing a plug having an expandable body designed to establish a tight seal with the walls of a well when expanded and means operable by the 35 application of pressure to expand the body to an operative position.

Another object of the invention is to provide a device of the above-mentioned character which is simple and durable in construction, reliable 40 and efficient in operation and inexpensive to manufacture.

Other objects and advantages of the invention will be apparent during the course of the following description.

50 In the accompanying drawings, forming a part of this specification and in which like numerals are employed to designate like parts throughout the same,

Fig. 1 is a longitudinal section view of the packing device, showing the relative position of the parts in contracted position, the sections of the three wall-gripping rings being taken on the lines *a*, *b* and *c*, respectively, of Fig. 6.

55 Fig. 2 is an elevational view of the central post,

pressure screw, and anchor member, with a part of the post shown in cross section,

Fig. 3 is a longitudinal sectional view of the wrench for turning the pressure screw,

Fig. 4 is a top plan view of the central post,

Fig. 5 is a side elevation of one of the wall-gripping rings,

Fig. 6 is a top view of the ring shown in Fig. 5,

Fig. 7 is a horizontal section of one set of expansion jaws, with the jaws in expanded position,

Fig. 8 is a view similar to Fig. 7, with the jaws in contracted position,

Fig. 9 is a side elevation of the packing device in expanded position, the upper and lower ends 15 being in longitudinal section to show a driving type of pressure applying means and anchoring foot for use with the same,

Fig. 10 is a longitudinal section of a modified type of packing device,

Fig. 10a is an enlarged detail section of the groove for holding the sealing paste,

Fig. 11 is an end view of the packer shown in Fig. 10, and

Fig. 12 is a cross section taken on line 12—12 25 of Fig. 10.

In the drawings, wherein for the purpose of illustration I have shown the preferred embodiments of my invention, the numeral 5 denotes a tubular expandable body, constructed of rubber 30 or other suitable material, which is mounted on a supporting frame consisting of upper and lower disks 6 and 7 connected together by a plurality of rods 8, secured to the disks by nuts 9. The rods 8 are arranged around the center of the 35

disks, in spaced relation, and disposed between the disks and within the area surrounded by the rods is a central longitudinal post 10 which is substantially square in cross section with its corners notched, as at 11, to receive the rods 8, which 40

serve to guide the post in its longitudinal movement. The upper end of the post 10 is provided with a central circular recess 12 to receive the nose 13 of a pressure screw 14, establishing a swivel connection between the pressure screw and 45

post. The screw 14 is rotatably connected to the upper end of the post 10 by a clamping plate 15 which is mounted in an annular groove 16 formed in the screw directly above the nose, the plate being fixedly attached to the upper end of the 50

post by bolts 17. A bushing 18 is mounted on the screw 14 above the plate 15 having interior screw threads for engagement with the right hand threads 19 formed on the screw. The lower end of the bushing is provided exteriorly with 55

left hand screw threads 20 for engagement with the threads of an opening 21 through the center of the upper disk 6 and the upper end of the bushing is conical shape and provided with right hand screw threads 21', the purpose of which 60

60

will be set forth hereinafter. The pressure screw 14 extends above the bushing and its extreme upper end 22 is of hexagonal shape in cross section to engage in a correspondingly shaped socket 23 of a wrench 24. The socket 23 is formed within the bore 25 of the wrench body, the bore above the socket being circular in cross section, and below the socket it is conical shape, as at 25', and provided with screw threads 26, for engagement with the conical threaded end 21' of the bushing 18. The upper end of the wrench body is reduced and threaded, as at 26', for connection with a string of well tubing, not shown, by means of which the wrench is turned. With the end 22 of the pressure screw 14 engaged in the socket 23 of the wrench, a turning of the wrench will rotate the pressure screw which is caused to move downwardly by the screw threads 19, thereby exerting a downward pressure on the post 10. If it is desired to retract the post 10, the wrench is lowered on the pressure screw to disengage the upper end of the screw from the socket 23 and bring the conical end of the wrench into engagement with the conical end of the bushing 18, so that by screwing the wrench down on the bushing, the bushing is turned in the disk 6 and by reason of the left hand threads 20 the bushing moves upwardly from the disk carrying the pressure screw with it, thus retracting the post. Rotation of the post is prevented by engagement of the square socket 27' in the lower end of the post with the square upper end 27 of a shaft 28 which is fixedly secured in the lower disk 7 by a nut 29. The shaft extends downwardly through a central opening 30 in the closed lower end 31 of the body 5 and secured on the lower end of the shaft 28, by nuts 31', is a substantially U-shape spring anchor member 32 adapted to grip the walls of the well hole and hold the body 5 against rotary movement when the pressure screw is turned.

The post 10, at spaced intervals throughout its length, is provided with recesses 33 in each of its sides and on each side of the recesses are apertured ears 34 between which one end of the lugs 35 are pivotally mounted by means of pivot pins 36. The opposite ends of the lugs 35 are pivotally connected to arcuate shaped jaws 37, the inner wall of which are provided with central recesses 38 in which the lugs are pivotally secured by pivot pins 39. The lower edges of the jaws rest on supporting plates 40 mounted on the rods 8 which are held against movement on the rods by cotter pins 41. Each set of jaws when expanded forms a perfect circle, as shown in Fig. 7, applying an equal pressure around the entire wall of the body 5, the adjacent ends of the jaws being, respectively, provided with interfitting tongues 42 and slots 43 which permit contraction of the jaws, as clearly shown in Fig. 8. When the post 10 moves downwardly, the lugs 35 swing outwardly and slide the jaws 37 laterally against the inner wall of the body 5, thereby expanding the body 5 to effect a seal between the body 5 and wall of the well at those points where the expansion jaws are located. To establish a tight fit between the body 5 and wall of the well the body is provided, at points opposite each set of expansion jaws, with wall-gripping rings 44 which are seated in annular grooves 45 formed in the outer wall of the body. These rings are more clearly shown in Figs. 5 and 6 and consist of a metal ring split circumferentially, as at 46, to form the interlapping sections 47, 48 and 49, the section 48 being transversely cut at the point 50

and freely expansible for the greater portion of its length. The outer face of the section 48 is tapered to form a sharp ridge normally disposed on a plane with the outer faces of the sections 47 and 49 which are split transversely at the point 51 to allow full expansion of all the ring sections. On each side of the ring grooves 45 the outer wall of the body is provided with additional annular grooves 52 for holding a paste compound 53 which when pressed into the wall of the well will effect a seal that will resist acids and other foreign elements found in salt water.

In Fig. 9, a slightly modified form of the device is shown which is of identically the same construction as the device heretofore described with the exception of the pressure applying means and anchor means at the bottom. In some instances, it is desirable to apply a driving force to actuate the post 10 and expand the body 5 into sealing engagement with the walls of the well. In order to operate the device by a driving force, which is supplied by a string of drilling tools, the pressure screw 14 and bushing 18 are removed and a drive rod 54 is inserted through the opening in the disk 6 and threaded into the socket in the upper end of the post 10, as at 55. A head 56 is formed integral with the upper end of the rod 54 and upon striking the head 56 a blow, the post 10 is moved downwardly to expand the body 5. When this method of expanding the body is employed the anchor member 32 is removed and a post 57 is threaded on the lower end of the shaft 28, the lower end of the post having a relatively large base 58 which rests on the bottom of the well.

In Figs. 10, 11 and 12 another form of the device is shown consisting of a tubular member 59 and post 60, telescopically fitted together. The outer ends of the member 59 and post 60 are provided with enlarged heads 60' and mounted between the heads is a tubular expansible body 61, provided in its outer wall with gripping rings 62 and sealing paste-holding grooves 63. The inner wall of the tubular member 59 has a series of annular ratchet teeth 64 which are engaged by the spring pressed latches 65 carried in the walls of the post 60. The latches are disposed in longitudinal slots 66 formed in the walls of the post, one end of the latches being loosely connected to the bottom of the slots by bolts 67, while the opposite ends are normally pressed outwardly by coil springs 68 seated in pockets 69 in the bottom of the slots. When the post and tubular member are pressed together by a driving force, the body 61 is compressed between the heads 60', expanding the body into gripping engagement with the walls of the well, and the body is locked in its expanded position by the latches 65 engaging the teeth 64 as the post and the tubular member slide together.

In operation, when a break occurs in the walls of a well admitting water into the well, the packing device or plug is lowered into the well by use of a string of well tubing which connects with the upper end of the wrench body 24 disposed on the upper end of the pressure screw 14 with its conical end in threaded engagement with the upper end of the bushing 18. After the plug is properly positioned with respect to the break in the well, the well tubing is turned to release the wrench 24 from connection with the bushing 18 and is then raised to bring the socket 23 of the wrench into engagement with the hexagonal upper end of the pressure screw. By rotating the well tubing the wrench turns the pressure screw 14 which

moves downwardly by the action of the screw threads 19, thereby exerting a downward pressure on the post 10, which through the lugs 35 force the jaws 37 laterally to expand the flexible body 5 into engagement with the walls of the well. A tight seal is effected between the body 5 and walls of the well by the expansible gripping rings 44 and the sealing paste in the grooves 52 which is pressed into the walls by the expansion of the body 5. If it is desired to re-adjust the plug after the same has been set, the wrench 24 is lowered on the pressure screw to bring its conical end into engagement with the upper end of the bushing 18 and by then screwing the wrench down on the bushing, the bushing, by reason of the left hand threads 20, is caused to move upwardly raising the pressure screw and post 10 to retract the jaws 37 and release the body 5 from engagement with the walls of the well. In some instances, circumstances require that a driving force be used to set the plug in place, the force being supplied by a string of drilling tools. If a driving force is to be employed to set the plug, a driving rod 54 is substituted for the pressure screw and a post 57 is attached to the shaft 28 in place of the anchor member 32, as shown in Fig. 9. As the rod 54 is directly connected to the post 10, the striking of the rod 54 with a string of drilling tools will move the post 10 downwardly, thus actuating the lugs 35 to move the jaws 37 laterally and expand the body 5. The modified type of plug shown in Figs. 10, 11, and 12 is also set by applying a driving force to move the telescoping post 60 and tubular member 59 together, which expands the body 61 into sealing engagement with the walls of the well. The tubular member and post are locked together by the latches 66 carried by the post which engage the ratchet teeth 64 formed in the inner walls of the tubular member. In all of the various types of packing devices shown in my drawings the flexible body is expanded into sealing engagement with the walls of the well, by expansion means operable by the application of pressure. The pressure may be supplied by a screw rod or driving rod depending on the drilling equipment which happens to be available at the time the packing device is set in the well. All types are equally effective in shutting off the flow of water and function in substantially the same manner.

It is to be understood that the forms of my invention herein shown and described are to be taken as preferred examples of the same and that certain changes in the shape, size and arrangement of the parts may be made without departing from the spirit of the invention or the scope of the subjoined claims.

Having thus described my invention, I claim:

1. A well packing device comprising a tubular flexible body, expansible jaws mounted in said body at spaced intervals for expanding said body uniformly throughout its length, and reciprocable means for actuating said jaws.
2. A well packing device comprising a tubular flexible body, wall-gripping rings mounted in the outer wall of said body, sealing paste-holding grooves surrounding said body on opposite sides of said rings and means for expanding said body.
3. A well packing device comprising a tubular flexible body, expansible jaws mounted in said body, at spaced intervals, wall-gripping rings surrounding said body opposite said jaws and means for expanding said jaws.

4. A well packing device comprising a tubular flexible body, a plurality of sets of expansible jaws mounted in said body at spaced intervals, the jaws of each set being arranged circumferentially of the inner wall of said body and having 5 interfitting tongues and slots in their adjacent ends, and means for expanding said jaws.

5. A well packing device comprising a tubular flexible body, a plurality of sets of expansible jaws mounted in said body, the jaws of each set 10 being arranged circumferentially of the inner wall of said body, a central post mounted to reciprocate in said body and means connecting said post with said jaws for expanding and contracting said jaws when said post is moved. 15

6. A well packing device comprising a tubular flexible body, a central post mounted to reciprocate in said body, expansible jaws actuated by said post for expanding said body, and pressure screw mounted in the upper end of said body 20 for reciprocating said post.

7. A well packing device comprising a tubular flexible body, a central post mounted to reciprocate in said body, expansible jaws actuated by said post for expanding said body, and a driving 25 rod slidably mounted in the upper end of said body for moving said post to expand said jaws.

8. A well packing device comprising a tubular flexible body, a central post mounted to reciprocate in said body, expansible jaws actuated by 30 said post for expanding said body, means at the upper end of said body for moving said post, and anchoring means at the lower end of said body.

9. A well packing device comprising a tubular flexible body, a central post mounted to reciprocate in said body, expansible jaws actuated by 35 said post for expanding said body, means in the upper end of said body for moving said post, and a spring anchor member at the lower end of said body to hold said body from turning. 40

10. A well packing device comprising a flexible tubular body, upper and lower disks mounted in said body, a plurality of rods extending between said disks and connected thereto, a central post 45 mounted to reciprocate between said rods and guided thereby, a shaft mounted in said lower disk and extending below the bottom of said body, an anchor member connected to the lower end of said shaft, expansible jaws connected with 50 said post for expanding said body, and means mounted in said upper disk for actuating said post.

11. A well packing device comprising a flexible body, upper and lower disks mounted in said body, 55 a plurality of rods extending between said disks and connected thereto, a central post mounted to reciprocate longitudinally of said body, said post being guided by said rods, a series of plates mounted on said rods, at spaced intervals, expansible jaws slidably mounted on said plates, lugs connecting said jaws with said post adapted to expand said jaws upon downward movement of said post, anchor means connected to said lower disk, and means mounted in said upper disk for 60 moving said post downwardly. 65

12. A well packing device comprising a tubular flexible body, sealing paste holding means in the outer wall of said body and expansible jaws mounted within said body for expanding the body 70 into engagement with the wall of the well.
